(57) CLAIM

The ornamental design for spatula handle, as shown and described.

DESCRIPTION

FIG. 1 is a top perspective view of a spatula handle showing
my new design;

FIG. 2 is a bottom perspective view thereof;

FIG. 3 is an enlarged bottom plan view thereof, the spatula lower portion not shown for ease of illustration;

FIG. 4 is an enlarged top plan view thereof, the spatula lower portion not shown for ease of illustration;

FIG. 5 is an enlarged top perspective view thereof, the spatula lower portion not shown for ease of illustration; and,
FIG. 6 is an enlarged bottom perspective view thereof, the spatula lower portion not shown for ease of illustration.

The broken lines are environmental and are not part of the claimed design.
